UNITED STATES PATENT OFFICE.

ANDREW ECKMAN, OF GRANITE FALLS, MINNESOTA, ASSIGNOR OF ONE-HALF TO HANS A. MIKKELSON, OF SAME PLACE.

MACHINE FOR TRIMMING SPOKES.

SPECIFICATION forming part of Letters Patent No. 268,787, dated December 12, 1882.

Application filed May 22, 1882. (Model.)

To all whom it may concern:

Be it known that I, ANDREW ECKMAN, of Granite Falls, county of Yellow Medicine, and State of Minnesota, have invented a new Machine for Trimming Spokes, for the use of carriage and wagon makers in gaging and turning the tenons of wagon or carriage spokes or other tenons before inserting the same in the mortise, as will be shown by the accompanying model and drawings.

My invention relates to a machine for dressing and finishing the foot and shoulders which form the tenons of spokes for wheels; and the object of this invention is to provide a simple, economical, and efficient device for tapering the tenons on the inner ends of spokes and for forming the shoulders thereon; also, in providing a machine which may be used for forming tenons of different sizes.

20 My invention consists of a reciprocating sash with face and side knives for finishing and dressing the tenon, and in an organized machine, consisting of certain adjustable parts and a movable table for presenting the ends 25 of spokes to the cutting-knives, the parts being constructed, combined, and arranged with especial reference to their operation upon tenons of spokes for wheels, as will be hereinafter set forth and claimed.

30 In the annexed drawings, Figure 1 is a perspective view of my invention adapted for planing and forming the tenons and shoulders on spokes for wheels of vehicles. Fig. 2 is a perspective view of the bed-plate with the operating parts detached. Fig. 3 is a plan view of the spoke-carrying table detached from the machine. Figs. 4, 5, 6, and 7 are detailed views; and Fig. 8 is a rear view of the vertical reciprocating frame, showing the operating-40 lever.

In the accompanying drawings, A represents an upright rigid frame, within which is secured a vertical reciprocating sash, which is provided with a face-plate, a, in which is seated the transverse knife b, which is secured within a recess in the face-plate by set-screws. In the rear of sash a, opposite the lower edge of the knife b, is an opening, the lower edge of which is beveled, after the manner of a car-

penters plane, so that the tool will readily relieve itself of the shavings which are removed from the spoke. To the edge of this sliding sash, adjacent to the cutting-edge of the knife b, are secured in suitable dovetailed recesses, knives c c', one of which projects beyond the face of the plate b. These knives c c' are for forming the shoulder and for cutting off the tenon.

On the rear of the frame A, and to one side of the same, is secured the lever C, which is connected to the sliding sash by a link, d, which is pivoted or bolted at one end to the reciprocating sash a and at the other end to the operating-lever C. This operating-lever is embraced near its free end by a guide or strap, e, which is attached to one of the standards of the frame A.

The bed-plate B, as shown in Fig. 2, is cut away at the portion opposite to where the standards of the frame A are attached, so as to form a passage-way for the sliding sash. Attached to this bed-plate, opposite the frame A, is a bracket, B', for supporting the end of the table. This bed-plate B is provided near its rear end with a recessed portion, f, into which the guide or rest for the end of the spoke is secured.

Above the bed-plate B, near its end, and at a suitable distance from the reciprocating cutters, is pivoted a table or spoke-support, D, which is provided at its free or movable end with an extended portion, D', which is cut away, as shown, so as to form a recess in which the person operating the machine may stand, so as to have the operating-lever, spoke, 85 and the horn, or end of the movable table, within easy reach, so as to operate the parts.

Secured within the transverse recess in the pivoted table D, opposite the sliding sash a, is a raised plate, d, one edge of which is cut away so as to form an angle, as shown at d', Fig. 3. Above this plate d, which acts as a guide, is attached an adjustable foot, E, which is provided on its side nearest to the operator with an index or finger, g, which points toward suitable graduations, h, on the table. This slide or gage bar E has an upright foot at its end, which serves as a stop or bearing for the

spokes, and it is adjustable, so as to accommodate different sizes of tenons, the depth of the tenons to be cut being indicated by the gage.

Attached to the outer standard of the frame 5 A is a spring, F, the lower end of which abuts against the inner side of the movable table, so as to throw the spoke-carrying table away from the sliding sash. On the opposite side of the frame A is a set-screw, which limits the 10 play of the movable table toward the cutter. The outward play of the table is limited by vertical and transverse pins secured to the table and bracket B'.

Within the recess f, at the end of the bed- 15 plate B, is secured a T-shaped bracket, H, which is adjustable vertically. The cross-bar of this bracket is provided with a gage, B, which is adjustable transversely with the bed-plate B. These brackets or foot-rests are provided with suitable thumb-screws or other securing and adjusting means for attaching and retaining the same in position.

The knife c' is of the requisite length for cutting off the end of the spoke at the same 25 operation of forming the tenon and shoulder, and, if desirable, this knife may be dispensed with. These knives c c' are both secured removably to the frame.

The operation of this invention may be described as follows: The spoke upon which it is 30 desired to form the foot and shoulder is laid upon the table D, the foot being placed near the end of the table opposite the vertical reciprocating sash and against the slide E, which is adjusted according to the depth of the shoulder required, which depth will be indicated by a pointer and graduated scale on the table. The end of the spoke which will form the foot being placed between the cutter and slide E, 35 the table is pressed toward the knives, which are reciprocated, and remove a portion of the spoke, thus forming one side of the shoulder and tenon. To form the shoulder and tenon on the other side the spoke is reversed. To 40 form a single tenon with angular shoulder the gages E and H at the end of the bed-plate will be adjusted so that the central portion of the spoke will be parallel with the cutter b.

If desirable, the vertical and lateral adjustments H and G on the ends of the bed-plate 50 can be set so as to give any desired slope to the shoulders and sides of the tenon. The raising of the guide H, upon which the end of the spoke rests, gives the slope or bevel to the 55 shoulder or tenon, or forms the shoulder, which will be at an angle with the spoke, which is desirable in staggered wheels. The moving

of the block G transversely gives the slope to the sides of the tenon. After the shoulders and tenons are formed the lateral guide G at 60 the end of the bed-plate is set at one side, so that the spoke may lie at an angle with the face of the reciprocating cutter, the side knives being removed from the face-plate, when the foot of the spoke may be reduced to the desired bevel by the flat knife. The angular portion d' will act as a guide, over which the shoulder on the end of the spoke rests. This plate d is raised sufficiently to keep the shoulder of the spoke away from the table. 65

I reserve the right to make subsequent application for the improvements herein shown and described, but not claimed.

Having thus described my invention, what I claim as new, and desire to secure by Letters 75 Patent, is—

1. In a spoke-tenoning machine, the movable table D, provided with an adjustable gage-foot, E, and a raised bed, d, with an angular portion, d', in combination with the vertically 80 and laterally adjustable gages H and G, substantially as shown.

2. In an organized machine for forming the tenons of spokes, the combination of the vertical reciprocating cutter, bed-plate, and swinging table, provided with an adjustable gage-foot for holding the end of the spoke upon which it is desired to form the tenon against the cutter, and vertically and laterally adjustable rest for the end of the spoke attached to 90 the bed-plate for holding the end of the spoke in position and give the desired bevel to the shoulder and foot, substantially as described.

3. In a device for tenoning and beveling the ends of spokes, the combination of the following 95 organized instrumentalities: a bed-plate supporting a laterally-swinging spoke-carrying table, and vertical frame, with sash, provided with face and side knives and means for throwing the table away from the knives, and limiting its play both to and from the knives, said table being provided with an adjustable and graduated gage-foot, the bed-plate being provided near the pivoted end of the table with vertically and laterally adjustable rests for 100 the ends of the spokes and means for operating the cutters, substantially as shown and described.

In testimony whereof I affix my signature in presence of two witnesses.

ANDREW ECKMAN.
